DESIGN FOR A DRESS

Katheryn Rost, New York, N. Y.

Application September 22, 1938, Serial No. 80,032

Term of patent 3½ years

To all whom it may concern:

Be it known that I, Katheryn Rost, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged fragmentary view of the sleeve as seen from the side illustrating the tucking.

My design is characterized by the specific tucking on the upper waist and sleeve portions of the specific dress as shown.

I claim:

The ornamental design for a dress, substantially as shown and described.

KATHERYN ROST.
